UNITED STATES PATENT OFFICE.

JOSEPH MALONYAY, OF BUDAPEST, HUNGARY, ASSIGNOR TO JULIUS DONNER, OF BUDAPEST, HUNGARY.

BOX.

Application filed April 26, 1927, Serial No. 186,687, and in Hungary June 5, 1926.

This invention relates to boxes of the type used as containers for shoe polish, and more particularly for boxes of such type in which the lid is not frictionally secured, but the 5 turned-down flange of the lid is provided with means engaging, in the closing position, a circular groove in the body of the box.

The object of the invention is to provide a box as above specified which will be simple 10 in construction and adapted to be manufactured of the same material as, and at inconsiderably higher costs than, the ordinary boxes with frictionally secured lid. Further objects of the invention are to facilitate the 15 opening and closing of the box and to obtain tight closure without the use of a packing.

According to the invention, the means engaging the circular groove are produced by providing the turned-down flange of the lid 20 at two opposite portions of its circumference with narrow recesses so as to form internal feathers fitting into the groove of the body and catching therewith in the closing position. The internal feathers of the lid thus 25 cooperate with the groove of the body to positively lock the lid against lifting from its closing position. When putting on the lid, and before the feathers catch with the groove, the flange of the lid is, of course, 30 obliged to widen elastically at the recessed portions which widening involves a corresponding contraction transversely to the direction of widening. In order to eliminate any hindrance which the body of the box 35 might offer to such contraction, such portions of the flange as partake in the contraction may be bent outwards so that, on the periphery of the flange, there appear two bosses staggered by 90° in relation to the recesses. 40 It follows from the above-mentioned deformations to which the flange is subjected when the lid is put on, that the feathers are released from the groove by pressure at the bosses in the flange.

A flange with the said recesses and bosses affords, of course, no tight closure. According to the invention, tight closure is nevertheless obtained by forming the flange cylindrically at that portion or zone only which 50 comprises the recesses and bosses and making

the portion or zone joining to the top plate with a conical taper, the edge of the body being formed with a taper preferably of the same conicality and the circular groove being so distanced from the conical surface on the 55 body in relation to the distance of the feathers from the conical surface on the lid that when the feathers catch with the groove the cone of the lid is tightly pressed on to the cone of the body, the reaction of the latter 60 against compression being overcome by the locking engagement of the feathers with the groove, but becoming effective and causing the lid to be thrown off as soon as the feathers are released from the groove by lateral pressure applied against the lid flange between 65 its recessed portions.

A constructional form of the invention is shown, by way of example, in the accompanying drawings in which— 70

Figs. 1 and 2 are two central sections at right angles of a closed box, and Fig. 3 is a plan view from below of the lid alone.

The flange *a* of the lid *A* is formed only in the lower half cylindrically, while the upper half tapers in a conical surface *c* towards the top plate *b*. Two opposite portions of the cylindrical zone are impressed with narrow recesses *d*¹, *d*² extending in circumferential direction to a fraction less than a quarter of the periphery. Moreover, the cylindrical portion is formed with two bosses *e*¹, *e*² staggered in circumferential direction by 90° in relation to the recesses. 75

The body *B* has a tapering edge *f* with 80 the conicality of the upper zone *c* of the flange *a*. The well known circular groove *g* of the body *B* is so distanced from the conical surface *f* that when the internal feathers formed by the recesses *d*¹, *d*² catch with the 85 groove *g* the cone *f* is pressed into the cone *c* to secure tight closure.

What I claim is:—

A box of the type described, consisting of a body having a circular groove on its side 90 and a tapering edge, in combination with a lid having a turned-down flange comprising a tapering upper zone adapted to receive said tapering edge of the body, and a cylindrical lower zone provided at opposite circumfer- 100

ential portions with narrow recesses forming internal feathers adapted to catch with said groove in the closing position of the lid and positively lock said lid against lifting, but capable of being disengaged from said groove by compressing said flange between said recesses, said circular groove being so dis-

tanced from said tapering edge that by causing said feathers to catch with said groove said tapering zone of the lid is forced on to 10 said tapering edge of the body.

In testimony whereof I have hereunto set my hand.

JOSEPH MALONYAY
